McCarter & English, LLP

(57) **CLAIM**

The ornamental design for a component for circuit breakers as shown and described.

DESCRIPTION

FIG. 1 is a perspective view of a component for circuit breakers showing the new design.

FIG. 2 is right side view of the component of FIG. 1.

FIG. 3 is a left side view of the component of FIG. 1.

FIG. 4 is a front view of the component of FIG. 1.

FIG. 5 is a rear view of the component of FIG. 1.

FIG. 6 is a top view of the component of FIG. 1; and,

FIG. 7 is a bottom view of the component of FIG. 1.

In these drawings, the solid lines illustrate the claimed ornamental design, whereas any broken lines illustrate unclaimed subject matter and form no part of the claimed design.

1 Claim, 7 Drawing Sheets
